YARN WINDING DEVICE FOR SPINNING MACHINES

Johann Jacob Keyser, Grabenallee 16, Aarau, Switzerland

Filed Oct. 9, 1961, Ser. No. 143,739

Claims priority, application Germany Oct. 12, 1960
20 Claims. (Cl. 57—129)

The present invention relates to a yarn winding device especially for spinning machines or twisting machines, the term "yarn winding device" comprising those parts of a spinning machine which cooperate for winding the yarn into a cop. With spinning machines of customary structure, the yarn winding device comprises a driven spindle which is journaled in the spindle rail and is adapted to receive a yarn sleeve upon which the yarn is directly wound and together with the latter, following the winding up operation, forms the finished cop.

The heretofore known yarn winding devices of this type are rather expensive because each yarn winding device comprises a spindle the upper portion of which must have a length and thickness corresponding to the sleeve to be placed thereon. This means that on the respective spindles, only such cops can be produced the dimensions of which are adapted to the respective available spindle upper portions. Any material changes in the size of the cop require an exchange of the spindle upper portion, if not even of the entire spindle. Inasmuch as with these known spindles, the yarn sleeves are placed upon the spindles from the top, and the finished cops have to be withdrawn over the top of the spindles, considerable manual labor is required which, in addition thereto also requires a considerable total period of stoppage of the machine, i.e., a considerable loss in production.

Therefore, numerous attempts have been made in an effort to permit the withdrawal of the full cops and placement of the empty yarn sleeves on the spindle by mechanical means. These known attempts have, however, not resulted in a practical solution because the construction of such devices is far too expensive and in addition thereto, impedes the servicing of the machine.

It is, therefore, an object of the present invention to provide a yarn winding device which will overcome the above-mentioned drawbacks.

It is another object of this invention to provide a yarn winding device which will greatly facilitate the placing of the yarn sleeve and the withdrawal of the full cop.

It is also an object of the present invention to provide a yarn winding device as set forth in the preceding paragraphs, which will also bring about considerable advantages in the journailling of the sleeve receiving member.

These and other objects and advantages of the invention will appear more clearly from the following specification in connection with the accompanying drawings, in which:

FIGURE 1a is a longitudinal section through a first embodiment of a yarn winding device according to the invention.

FIGURE 1b represents a longitudinal section through a further embodiment of a yarn winding device according to the invention.

FIGURES 2a, 2b, 2c, 2d and 2e respectively illustrate different embodiments of annular holding means for use in connection with a yarn winding device according to the present invention.

FIGURES 3a and 3b respectively illustrate two embodiments of holding means for the lower end of a sleeve in a tubular member employed in connection with the yarn winding device of FIGS. 1a and 1b.

2

FIGURES 4a and 4b respectively illustrate further holding means for the lower end of a sleeve in a tubular member employed in connection with the yarn winding device of FIGURES 1a and 1b, respectively.

FIGURE 5 illustrates a further embodiment of a yarn winding device according to the invention.

FIGURE 5a is a cross section through a detail of FIGURE 5.

FIGURES 6a, 6b and 6c respectively illustrate, partially in section, further embodiments of yarn winding devices with a tubular body according to FIGURE 1.

FIGURES 7a, 7b and 7c respectively illustrate, in section, further yarn winding devices according to the invention with a tubular body employed in the arrangement of FIGURE 1b.

General Arrangement

The yarn winding device according to the present invention, which is radically different from heretofore known devices of the type involved, is characterized primarily by a rotatably and drivingly arranged tubular body and by at least one yarn sleeve placed in the interior of said tubular body, said yarn sleeve being held at the upper end of the tubular body as a shankless yarn carrier.

Thus, in conformity with the present invention, no yarn sleeve is any longer placed or slipped over the upper portion of a spindle but is held from the outside by a tubular body whereby a spindleless yarn carrier is formed. This arrangement greatly facilitates the insertion of the yarn sleeve and the withdrawal of the full cop. This easier handling is due to the fact that the heretofore known slipping-over of the yarn sleeves on a spindle upper portion as well as the withdrawal of the full cop from said spindle upper portion at a relatively long servicing stroke, has been eliminated.

Furthermore, also with regard to journailling and driving of the tubular body, considerable advantages are obtained over the heretofore known spindles.

For holding the yarn sleeve in the tubular body, the yarn sleeve placed into the interior of the tubular body may be axially displaceable along the inner wall of said tubular body while being held in its respective position by friction. To this end, at least two holding means may be provided which engage the wall of the yarn sleeve. One of these holding means may be arranged at that end of the tubular body which faces the sleeve, whereas the other holding means may be engaged by the inner wall of the tubular body. The yarn sleeve is thus embraced at two portions and is secured against an inclination or tilting movement. Due to this way of locating and securing the yarn sleeve on the tubular body, the unity of the yarn winding device is established so that rotation of the tubular body will result in the same rotation of the yarn sleeve.

In order to obtain an insertion of the yarn sleeve into the tubular body and the holding thereof by friction or clamping action, the holding means may, in conformity with the present invention, be radially yieldable. In view of the shape of the holding means which are formed in conformity with the respective circumstances, it is possible to adapt the arrangement to various types of yarn sleeves. Also, the properties as to material of the holding means will permit great adaptability to the required friction and any desired damping of oscillations.

More specifically, the holding means may be formed by yieldable rings which, when widening the yarn sleeve and inserting the same, widen, and while developing a clamping tension, hold the yarn sleeve fast. According to a further development of the invention, the holding means may be formed by hollow elastic rings the inner pressure of which is variable, thereby creating the possibility of adapting the clamping tension to the weight

of the yarn sleeve and cops and to the length and the diameter thereof. A particularly easy insertion of the yarn sleeve may be obtained by a corresponding design of at least the uppermost holding means engaging the yarn sleeve. To this end, according to the present invention, at least the holding means arranged on that side of the tubular body end which faces the sleeve is adjustable from the outside toward the wall of the yarn sleeve in the radial direction until frictional engagement is obtained. Such an arrangement may be realized according to the present invention by placing the upper holding means on the upper end face of the tubular body and holding said upper holding means in axially and radially clamped position by an annular flange of a bushing surrounding the free end of the tubular body.

According to a further development of the invention, the bushing may, by a spring or the like, by means of its annular flange, be axially clamped against the end face of the tubular body and may, in its turn, axially and radially brace or clamp the elastically yieldable ring forming the holding means. The clamping force thus is dependent not only from the elastic ring but also from the spring force acting thereupon, so that the clamping force may be varied in a manner known in connection with an elastic ring subjected to inner pressure.

There also exists the possibility of clamping the bushing by spring force or the like, by means of a conically downwardly widening annular flange, axially against the end face of the tubular body. Such a plier-like embracement of the yarn sleeve by a clamping or holding means yields the same advantages as a disengageable clutch.

To adapt the holding means to various lengths of yarn sleeves, the location of at least the lower holding means in the tubular body may be variable over the length of said tubular body.

As to a corresponding design of the tubular body, various possibilities exist. According to one possibility, latch means or the like distributed on the inner wall of the tubular body over the length thereof, may be provided for holding the holding means in the tubular body. It is particularly advantageous to design the tubular body as a corrugated tube while axially arresting the holding means on the inwardly directed valleys of the corrugated tube. The corrugation makes it possible, without additional costs, to arrest the holding means on the interior of the hollow body in numerous ways while the valleys on the outside of the tubular body may be taken advantage of for very simply journaling or driving said tubular body.

In order further to adapt the yarn winding device to variously designed yarn sleeves and to secure the position of said yarn sleeves, it is possible, in conformity with the present invention, to design the holding means engaging the lower end of the yarn sleeves as a permanent magnet which is located and held on the inner wall of the tubular body by means of radially yieldable holding means. In this way, the yarn winding device will, without difficulty, also permit the winding of yarn upon yarn sleeves which consist completely of metal or have at least their lower end armed by iron or another metal adapted to be magnetized.

In order to assure the location of the lower yarn sleeve end in the radial as well as in the axial direction in a different way, it is also possible, with a corresponding design, to form the holding means engaging the lower end of the yarn sleeve as a supporting sleeve held on the inner wall of the tubular body while said supporting sleeve supports the yarn sleeve from below.

The above-mentioned embodiments are preferably designed for the insertion of the yarn sleeve into the tubular body from the top thereof. The holding means arranged on the inner wall of said hollow body will take care of assuring the location of the yarn sleeve. The withdrawal of the full cop is effected by pulling the same out of its mounting. The insertion of the next empty yarn

sleeve may be effected only after the full cop has been withdrawn. The most favorable solution of the problem underlying the present invention consists in making the tubular body open at both ends so that at least one yarn sleeve may be pushed through from below. Such an arrangement furnishes the possibility that when tilting the yarn sleeve carrying a finished cop, simultaneously a new sleeve be brought into its position, said sleeve being moved by the tubular body from below into its spinning position.

The new type of arrangement according to the present invention also yields various possibilities of designing the details of the arrangement according to the present invention. Thus, according to one embodiment, a holding means provided at the lower end of the tubular body is formed by a spring body which will be expanded when pushing through a yarn sleeve from below. The said spring body is provided with an inwardly directed extension or the like by means of which, following the pushing-through of the sleeve, said spring body catches below said sleeve and supports the same in the axial direction. In this way, the location as to height of the yarn sleeve is secured in a proper manner.

In addition thereto, a magazinization of yarn sleeves within the tubular body will be possible. According to a corresponding feature of the invention, a yarn sleeve insertable from below into the tubular body, is adapted to be moved out of the tubular body by means of a successive sleeve partially insertable from below in said first mentioned yarn sleeve. The said first mentioned yarn sleeve is movable out of the hollow body by said successive sleeve to such an extent that it will have only its lower end in the tubular body. In this way, continuously from below, new yarn sleeves may be inserted into the tubular body while the sleeves insertable from below will only partially protrude from the tubular body and at the same time will form the holding means of the partially moved out yarn sleeve, which latter has only its lower end still in the tubular body and is available for the winding operation with the customary length. When the cop has been formed, the upper yarn sleeve with the cop may be lifted off, and the successive sleeve having its major portion still in the tubular body will then be able, by means of further successive sleeves, to be moved into spinning position. This arrangement yields additional safety with regard to the vertical locationing of the yarn sleeves in spinning position and may be used for further damping oscillations.

More specifically, the portion of the successive sleeve inserted into the preceding yarn sleeve may be reduced in diameter by the wall thickness of the first-mentioned sleeve so that the successive sleeve will, from the inside, support the lower end of the working sleeve.

If desired, the yarn sleeve may, in a manner known per se, be designed conically while the cone is so selected that a similarly designed successive sleeve will be adapted over a portion of its length to be inserted into the first sleeve from below.

The insertability of the yarn sleeves into the tubular body from below makes it possible to employ a special type of sleeves which have expandable sleeve portions. Therefore, the present invention is also characterized by the employment of a plurality of yarn sleeves adapted telescopically to be inserted into each other, which sleeves with their respective lower ends are adapted to be located in their respective position by holding means. Consequently, by means of the tubular body, it is possible to hold not merely two partially interengaging yarn sleeves but also a plurality of yarn sleeves or a yarn sleeve of a plurality of telescopically interengaging parts. The respective inner sleeve or sleeve portion forms, so-to-speak, the shank for the next sleeve or sleeve portion thereabove. As will be evident from above, the yarn sleeves form a spindleless yarn carrier.

Structural Arrangement

Referring now to the drawings in detail, the arrangement shown in FIGS. 1a and 1b illustrates a yarn winding device according to the present invention with a tubular body 1 and 101, respectively, which is rotatably and drivingly journaled in the spindle rail. The spindle rail may either be U-shaped or may be designed in the form of a housing box, but may, of course, also be of other suitable shape. In the particular embodiment shown in the drawing, the lower housing wall 2' and the upper housing wall 2" of the spindle rail are shown. In the lower housing wall 2' there is arranged the anti-friction bearing 3, whereas the upper housing wall 2" supports the anti-friction bearing 4.

According to the embodiment of FIG. 1a, the tubular body 1 consists of an outer smooth tube section so that the anti-friction bearings 3 and 4 can be mounted thereon without difficulty.

According to the embodiment of FIG. 1b, the tubular body 101 is designed as a corrugated tube so that it is possible to allow the anti-friction body of the bearings 3' and 4' to move in a valley of said tubular body 101 without the necessity of providing an inner race ring for the respective bearing. In the upper housing wall 2" above the anti-friction bearing 4 in a bore 5a there is mounted a sleeve 5 which serves as protective means against the entry of lint or the like. The tubular body 1, 101 respectively extends through sleeve 5 and freely protrudes beyond the upper housing wall 2" of the spindle rail. The free end of the tubular body 1, 101 respectively is provided with an outwardly directed flange 6 against which rests one end of a spring 7. Spring 7 has its lower end resting against a spring ring 8 which, in its turn, is held in bushing 9. The upper end of bushing 9 extends inwardly above flange 6 of the tubular body 1, 101 respectively and, together with the flange 6 clamps therebetween an elastic annular body 10. According to FIG. 1a, the elastic annular body 10 is shown in a condition in which spring 7 has not yet exerted any deforming effect on said annular body 10.

FIG. 1b shows that the clamping force exerted by spring 7 upon the elastic annular body 10 presses in the axial direction so that it fully rests against the portion surrounding said annular body 10 and deforms the latter radially inwardly so that the yarn sleeve 11 inserted in the tubular body 1, 101 is firmly held in its respective position by friction. The annular body 10 alone establishes a connection between the tubular body 1, 101 respectively on one hand, and the inner sleeve 11 on the other hand which will convey a rotative movement imparted upon tubular body 1, 101 upon the yarn sleeve 11. Since, however, the yarn sleeve 11 has to be held properly along the longitudinal axis of the tubular body 1, 101 respectively, at least two holding means are required which engage the wall of the yarn sleeve 11. To this end, according to the embodiment of FIG. 1a, the inner wall of the tubular body 1 is at uniform distances provided with a greater number of groove-shaped recesses 12 which are distributed over the entire length of the tubular body 1 and are adapted to receive annular holding means.

According to the embodiment of FIG. 1b, the valleys on the inside of the corrugated tubular body 101 receive such annular holding means. According to FIGS. 1a and 1b, near the upper end of the tubular body 1, 101 respectively there is provided a further holding means in the form of an elastic ring 13 engaging a recess 12 of the tubular body 1 or a valley of the tubular body 101, so that the inner circumference of the elastic ring 13 engages the outer wall of the yarn sleeve 11 under friction. Arranged in one of the recesses 12 located therebelow and pertaining to the tubular body 1 or in a corresponding valley of the tubular body 101, is a further elastic supporting ring 14 supporting the lower end of the yarn sleeve 11 in the axial direction. The seat of the yarn sleeve 11

5 inserted in the tubular body 1, 101 respectively is in this way properly secured by the elastic annular body 10, the elastic ring 13 and the elastic supporting ring 14 inasmuch as at least the annular body 10 and ring 13 will frictionally engage the yarn sleeve 11. Due to the present greater number of free recesses 12 on the tubular body 1 and the valleys on the corrugated tubular body 101, there exists the possibility to provide further elastic rings 13 and to cause the same to engage the wall of the yarn sleeve 11. Similarly, it is possible to arrange the elastic supporting ring 14 in conformity with the length of the yarn sleeve 11 to be supported in any one of the recesses 12. In this way, a great adaptability to the various dimensions of yarn sleeves prevails.

10 FIGS. 1a and 1b also show possibilities for driving the tubular body 1, 101. For instance, the tubular body 1 may be driven by means of a band 15 which either directly engages the outer surface of the tubular body 1 or engages a whorl sleeve 16 mounted on the tubular body and consisting of a frictional material. The drive of the tubular body 101 may, for instance, be effected by means of a cord 17 which engages a valley section on the outside of the tubular body 101. If a single cord 17 should not suffice, a second cord or additional cords may engage corresponding further valley sections of the tubular body 101 as driving means.

15 FIGS. 2a to 2e respectively illustrate various annular holding means which may be arranged at those portions where the elastic annular body 10, the elastic ring 13, or the elastic supporting ring 14, may be provided. According to FIG. 2a, ring 18 has a round cross-section and is also circular when seen from the top, as shown in FIG. 2b in the form of a ring 19 having a somewhat larger diameter and cross-section. Ring 20, according to FIG. 2c, is of hexagonal shape when seen from the top. A further embodiment of an annular holding means is shown in FIG. 2d according to which the holding means is designed as a wire spiral 21 which makes it possible, in view of an inclined position of the individual windings, to obtain a widening of the holding means in conformity with the requirements. FIG. 2e shows a hollow elastic ring 22 forming a holding means the inner pressure of which is variable, for instance, by increasing or decreasing the air pressure through the intervention of valve 23. With such hollow ring 22, the adaptability to various diameters of yarn sleeves is increased without requiring an exchange of the holding means. By varying the air pressure, also the force for pressing the ring against the yarn sleeve or the oscillation damping characteristic thereof, may be varied. The same object may be obtained with rings according to FIGS. 2a to 2d by adapting the dimensions or the elastic properties of the rings to the respective requirements.

20 55 There exist further possibilities for the design of the holding means arranged at the lower sleeve end. Instead of the supporting ring 14, according to FIGS. 3a and 3b, a holding means may be provided in the form of a permanent magnet which supports a yarn sleeve 11 from below. The permanent magnet 25 is by means of rings 13, 14 held fast in the tubular body 1, 101 respectively. Rings 13 50 may, for instance, be designed similar to the rings 18, 19 or 20 or according to FIGS. 2a to 2c. The rings 13, 14 either directly engage depressions 12 in the tubular body 1 or valley sections of the tubular body 101. The lower end of the yarn sleeve 11 is provided with the annular body 24 which consists of yarn or a magnetizable metal and which is pulled downwardly by the permanent magnet 25 having a definite location in axial direction so that the location of the yarn sleeve 11 will likewise have a definite location in the axial direction. The lower end of yarn sleeve 11 is laterally held by the holding ring 13 in the radial direction, which ring also serves for holding the permanent magnet 25. With a corresponding elasticity of the holding ring 13, the yarn sleeve 11 retains

7 laterally a certain play so that the yarn sleeve will be able, during rotation, to adjust itself to the line of gravity.

FIGS. 4a and 4b show the design and arrangement of a sleeve-like holding means 26 which supports the lower end of the yarn sleeve 11. The bead 27 at the upper end of the holding means 26 directly engages a depression 12 of the annular body 1, as shown in FIG. 4a, or engages a valley section of the annular body 101, as shown in FIG. 4b. The lower end of the sleeve-like holding means 26 has an inwardly protruding section 28 supporting the lower end of yarn sleeve 11, the outer wall of which additionally engages the inner circumference of bead 27. Due to the elastic design of the sleeve-like holding means 26, also in this instance there exists the possibility that the 15 yarn sleeve 11 will be able, during its movement, to follow the oscillations which may occur.

FIG. 5 illustrates a further embodiment of a tubular body according to the invention. The two tubular bodies 1 are, by means of the anti-friction bearings 3 and 4, rotatably journaled in a common spindle-box 2, as it may be employed, for instance, in connection with two-sided machines. From FIG. 5 it will be evident how, for instance, the drive of the tubular body 1 may be effected by means of a belt. In the longitudinal direction of the spindle-box 2 extends a driving shaft 31 having connected thereto belt driving pulleys 32. The driving belts 33 are so arranged that they directly embrace the tubular body 1. The yarn winding device illustrated in FIG. 5 is somewhat differently designed with regard to the embodiment of FIG. 1a. In addition to the journaling of the tubular body 1 which journaling corresponds to that of the embodiment of FIG. 1a, similarly, depressions 12 are provided on the inner wall of the tubular body 1, said depressions 12 being provided in any desired number. At the lower end of the tubular body 1 there is provided a sleeve-like holding means 26, as has been described in detail in connection with FIG. 4a. The lower end of the sleeve-like holding means 26 is open similar to the tubular body 1. Inasmuch as the holding means 26 is elastic, it may be widened so that a conical yarn sleeve 34 can be introduced from below. Such yarn sleeve may be passed through the sleeve-like holding means 26 and the hollow body 1 to such an extent that it will occupy the position illustrated on the left hand side of FIG. 5 in which sleeve 35 has its lower end resting upon the upper end of yarn sleeve 34 and, together with the latter is radially clamped by means of the holding means arranged at the upper end of the tubular body 1. At the upper portion of the tubular body 1, the connection between the tubular body 1 and yarn sleeve 35 has been established in a manner different from that shown in FIG. 1a. Similar to the latter, above the anti-friction bearing 4 there is provided the sleeve 5. Also flange 6, spring 7, spring ring 8, and bushing 9 are provided. However, the inwardly protruding portion of bushing 9 which extends over flange 6 has a special design. According to the embodiment of FIG. 5, the inner circumferential portion 36 of the annular flange of bushing 9 is conical and flares downwardly. Within the annular flange there are provided correspondingly conical segments or ring sectors 37 in spaced arrangement with regard to each other, as is clearly evident from the cross-section of FIG. 5a. When the bushing 9 moves in the axial direction under the influence of spring 7, ring sectors 37 are clamped against the outer wall of yarn sleeve 35 in radial direction, so that a plier-like holding of the yarn sleeve 35 will be assured.

With the embodiment according to FIG. 5, the yarn sleeve 34 represents a successive sleeve which supports the lower end of the yarn sleeve 35 in winding position. Cop 38 is to be wound upon yarn sleeve 35. When cop 38 has been completed, yarn sleeve 35 with cop 38 thereon is, following a slight lifting of bushing 9 and the loosening of the ring sectors 37 inherent thereto, withdrawn in upward direction out of the tubular body 1 from the yarn

5 sleeve 34, as has been shown on the right-hand side of FIG. 5. Thereupon, yarn sleeve 34 may be brought into the position which previously was occupied by yarn sleeve 35. This is effected by pushing a further yarn sleeve 39 from below upwardly, which will now move into the position of yarn sleeve 34. Thus, from withdrawal to withdrawal, a full cop may be replaced by sleeve after sleeve from below. For purposes of removing a completed cop, a slight lifting off of the latter is required in order to strip the same over the upper end of that yarn sleeve which at the respective time is in the interior of the tubular body 1.

This lifting off of the cops requires that at least the clamping force of the holding means 37 at the upper end of the tubular body 1 will be overcome. For purposes of relieving the clamping tension of this holding means, it is sufficient to displace bushing 9 upwardly against the thrust of spring 7 whereby the holding means 37 will be deprived of the radially inwardly directed force. Thereupon, no difficulties will exist in withdrawing the yarn sleeve with the cop from the upper end of the tubular body 1. This will be evident from the illustration on the right-hand side of FIG. 5.

Instead of the sleeve-like holding means 26 shown in FIG. 5 and provided at the lower end of the tubular body 1, the same holding arrangement may be provided as has been described, at the upper end of the tubular body 1.

FIGS. 6a and 6b illustrate further embodiments of a yarn winding device according to the invention while the device corresponds substantially to the parts of the embodiment of FIG. 1a. The hollow body 1 is in the same manner rotatably journaled in the lower housing wall 2' by means of the anti-friction bearing 3 and is also rotatably journaled in the upper housing wall 2" by means of the anti-friction bearing 4. Furthermore, the hollow body 1 may, for instance, be driven by a belt. Also, sleeve 5, flange 6 of tubular body 1, spring 7, spring ring 8, bushing 9 and the elastic annular body 10 are similarly designed as the corresponding parts in the embodiment of FIG. 1a. The differences over said last-mentioned embodiment consist merely in that the insert opening in the lower housing wall 2' is closed by a cap 49 so that with the illustrated embodiment, the yarn sleeves must be inserted into the tubular body from above. With the embodiment according to FIG. 6a the elastic annular body 10 does not directly engage yarn sleeve 41 because the latter has its lower end provided with resilient rings 42, as is the case, for instance, with the known Northrop sleeves for woof bobbin change automats. In this instance, between the elastic annular body 10 and the yarn sleeve 41 there is clamped in a holding sleeve 43 which is slit in the axial direction and has its lower edge provided with a folded-over edge 44 adapted to engage a depression 12 of the tubular body 1. The holding sleeve 43 furthermore comprises a number of annular grooves 45 which, as to number and design, correspond to the resilient rings 42 of yarn sleeve 41. In this way, yarn sleeve 41 is inserted into holding sleeve 43, and, by means of the elastic ring 10, is clamped into sleeve 43 in such a way that simultaneously, there is also established the connection with the tubular body 1.

The embodiment according to FIG. 6b is designed for receiving a conical yarn sleeve 46 which is held on one hand by the elastic annular body 10 in direct frictional connection, and on the other hand is held by the elastic supporting ring 14 at the lower end, the supporting ring 14 engaging a depression 12 of the tubular body 1.

The embodiment according to FIG. 6c is designed substantially in the same way as the embodiment of FIG. 6b, but it differs therefrom in that, instead of a lower supporting ring 14, there is provided a permanent magnet 25, as it has been described in connection with the embodiment of FIG. 3a. This permanent magnet 25 is positively held by means of two holding or supporting rings 75, 14 which engage depressions 12 of the tubular body

1. Yarn sleeve 47 rests upon the permanent magnet 25 and is pulled inwardly into the tubular body 1 by such permanent magnet 25. Furthermore, the yarn sleeve 47 is laterally embraced by the holding ring 13, as it has been described in connection with the embodiment of FIG. 3a. In addition thereto, a ring 48 of iron or magnetizable metal may be inserted into the lower end of yarn sleeve 47 so that the magnet may become effective. In this connection, it is assumed that the yarn sleeve 47 consists of non-magnetizable material as, for instance paper or the like. Of course, if desired, the entire yarn sleeve may consist of magnetizable material.

The embodiments according to FIGS. 6a to 6c have in common that the lower holding means for the yarn sleeve 41 or 46 or 47 may be displaced to different levels within the tubular body 1, and that various types of holding means may be employed. Due to the fact that the holding of the yarn sleeves in tubular body 1 is effected by means of elastic annular bodies 10 or supporting rings 14 or permanent magnets 25, the yarn sleeves 41 or 46 or 47 will not be subjected to a rigid clamping. They are, rather, able to move laterally to a certain extent, with the result that they will center automatically with regard to the axis of rotation of the tubular body 1 in such a way that the axis of rotation will coincide with the axis of gravity of the yarn sleeve including the wind-up yarn body.

FIGS. 7 to 7c illustrate further embodiments of the invention while employing a tubular body 101 in the form of a corrugated pipe. With the embodiment according to FIG. 7a, the tubular body 101 is in the same manner as with the embodiment of FIG. 1b, journaled in the lower housing wall 2' and upper housing wall 2'' by means of anti-friction bearings 3' and 4' respectively. Similarly, the sleeve 5, flange 6 of tubular body 101, spring 7, spring ring 8, bushing 9 and elastic annular body 10, are provided. However, with the embodiment according to FIG. 7a, the yarn sleeve 51 is connected to the tubular body 101 in a manner different from that of FIG. 1b. More specifically, a supporting sleeve 52 is placed into the tubular body 101 and has about one-half of its length arranged within the tubular body 101, while the remaining length protrudes beyond the upper end of the tubular body 101. However, this supporting sleeve 52 has a greater length which extends beyond the total length of the tubular body 101 and protrudes beyond the tubular body 101 by about the same length. The lower end of the supporting sleeve 52 is provided with a reinforcement 53 and has an annular groove engaged by the holding ring 54 which, on the other hand, engages a valley section of the tubular body 101. The employment of a supporting sleeve is particularly advantageous when the yarn sleeve has to be selected with a very thin wall, for instance for saving weight and space. The lower end of yarn sleeve 51 has an annular groove 55 formed by a corrugation. The yarn sleeve 51 is slipped over supporting sleeve 52 to such an extent that annular groove 55 of yarn sleeve 51 will be engaged by the elastic annular body 10. In this way, a frictional connection is established between the tubular body 101 and the yarn sleeve 51.

FIGS. 7b and 7c illustrate a yarn winding device according to a further embodiment of the present invention, said two figures respectively illustrating two different positions of the yarn sleeve. The tubular body 101 is in this instance journaled in the equatorial zone of a ball in the form of a two-line anti-friction bearing 56, this bearing forming the only bearing portion for the tubular body 101. The balls of the anti-friction bearing 56 move directly into corrugations of the tubular body 101, as is clearly shown in the drawing. The outer ring is mounted in the web or leg 57 of a T-shaped portion of the spindle rail and is thus held therein. The upper end of the tubular body 101 similar to the previous embodiment has a flange 6, a spring 7, a spring ring 8, a bushing 9 and an elastic annular body 10 which parts operate in the same

5

10

manner as described in connection with the previously discussed embodiments. Similar to the embodiment of FIG. 7a, the annular body 101 of FIG. 7b has mounted therein a supporting sleeve 58 which latter, however, has a greater length which extends over the total length of the tubular body 101 and protrudes therefrom by about the same length. The lower end of the supporting sleeve 58 is provided with the same reinforcement 53 as supporting sleeve 42 of FIG. 7a, and is also provided with an annular groove in which is mounted a holding ring 54 which latter is located in a corrugation of the tubular body 101. Placed upon the supporting sleeve 58 is, in this instance a two-sectional yarn sleeve the inner portion 59 of which has about the same length as the supporting sleeve 58, whereas the outer portion 60 has about half said length. Both sleeve portions have their lower ends provided with an annular groove 55 formed by annular folds, which groove 55 serves for securing the location of the sleeve portions within the tubular body 101 by friction. In the position of the yarn sleeve as shown in FIG. 7b, the inner portion 59 is completely slipped over the supporting sleeve 58 and rests upon the reinforcement 53 of the supporting sleeve 58 in the axial direction. To secure the position in the radial direction, there is provided a holding ring 54' which, on one hand engages the annular groove 55 on the inner portion 59 of the yarn sleeve, and on the other hand engages a valley section of the tubular body 101. The outer portion 60 of the yarn sleeve which is placed upon the inner portion 59 occupies such a position that the annular groove 55 of the outer portion 60 is filled by the elastic annular body 10 so that in this way also the outer portion 60 of the yarn sleeve is by friction connected to the tubular body 101. Furthermore, below the elastic annular body 10 a further holding ring 54' is inserted into a valley section of the tubular body 101. The holding ring 54' will, in the position of the yarn sleeve according to FIG. 7b, not engage the inner portion 59.

The winding operation starts on the outer portion 60 of the yarn sleeve and is continued until the winding tip 40 has almost reached the upper portion of the outer part 60 of the yarn sleeve. As soon as this is the case, the yarn sleeve is brought into the position of FIG. 7c. In this position, the outer part 60 will retain the position it occupied up to that time, whereas the inner portion 59 of the 45 yarn sleeve engages the holding ring 54''. In this way, the yarn sleeve is extended upwardly and the winding operation may pass from the outer portion 60 of the yarn sleeve to the inner portion 59 of the yarn sleeve and may be continued on said inner portion 59 until the winding 50 tips have reached the upper end of the inner portion 59 of the yarn sleeve.

FIGS. 7b and 7c also show two different possibilities for driving the tubular body 101. According to FIG. 7b, at uniform spacing from the anti-friction bearing 56 there is provided one driving cord 61 each in a valley section of the tubular body 101. In contrast thereto, according to FIG. 7c, instead of one driving cord there are always two driving cords 61 arranged above and below the anti-friction bearing 56.

60 The possibilities set forth in connection with the embodiments of FIGS. 6a to 6e may also be employed in connection with tubular bodies 101, as illustrated in FIGS. 7a to 7c. Similarly, the particulars according to FIGS. 7a to 7c may be employed in connection with smooth tubular bodies 1 according to FIGS. 5 and 6a to 6c.

65 The embodiments of yarn winding devices illustrating the tubular bodies are driven, for instance by means of a belt or a cord. It is a matter of course that there also exists the possibility of rotating the tubular body by other driving means, for instance by means of a screw wheel—worm transmission or by a drive of its own. In this connection, it is possible to design the hollow body as hollow drive shaft of an electric motor.

70 When employing a tubular body, there also exists the possibility of employing yarn sleeves of different shapes

75

and dimensions in the form of spindleless yarn carriers. Furthermore, the advantage is obtained that the yarn sleeves may be pressed upwardly from below. In each instance, due to the elimination of a spindle, the withdrawal of a completed cop is considerably facilitated because it will be possible to withdraw the cop by a mere slight tilting operation and only a slight axial upward movement.

It is, of course, to be understood that the present invention is, by no means, limited to the particular constructions illustrated in the drawings, but also comprises any modifications within the scope of the appended claims.

What I claim is:

1. In a yarn winding device, especially for spinning and twisting machines, supporting means, a substantially vertical tubular member rotatably journaled in said supporting means and adapted to receive therein at least a portion of a yarn sleeve for receiving a cop, first annular holding means arranged at the upper end portion of said tubular member and adjustable radially for selectively reducing its inner diameter to thereby frictionally engage and hold a yarn sleeve inserted through said holding means into said tubular member, second annular holding means supported by said tubular member in axially spaced relationship to said first holding means for likewise frictionally engaging and holding said yarn sleeve when inserted into said tubular member, and manually adjustable means arranged adjacent said first holding means for selectively adjusting the same.

2. In a yarn winding device, especially for spinning and twisting machines, supporting means, a substantially vertical tubular member rotatably journaled in said supporting means and adapted to receive therein at least a portion of a yarn sleeve for supporting a cop, first annular yieldable holding means supported by the upper end portion of said tubular member and adapted to allow the passage of at least a portion of said yarn sleeve therethrough when inserting said yarn sleeve into said tubular member, bushing means extending around said upper end portion of said tubular member and provided with flange means operable to engage said holding means and exert axial and radial pressure thereupon for selectively reducing the inner diameter of said first holding means to thereby exert a clamping and holding action on the yarn sleeve inserted into said tubular member, and at least second annular holding means supported by said tubular member and arranged in axially spaced relationship to said first holding means for frictionally engaging and holding a yarn sleeve inserted into said tubular member.

3. In a yarn winding device, especially for spinning and twisting machines, supporting means, a substantially vertical tubular member rotatably journaled in said supporting means and adapted to receive therein at least a portion of a yarn sleeve for supporting a cop, first annular yieldable holding means supported by the upper end portion of said tubular member and adapted to allow the passage of at least a portion of said yarn sleeve therethrough when inserting said yarn sleeve into said tubular member, bushing means extending around said upper end portion of said tubular member and provided with flange means operable to engage said holding means and exert axial and radial pressure thereupon for reducing the inner diameter of said first holding means to thereby exert a clamping and holding action on the yarn sleeve inserted into said tubular member, abutment means supported by said bushing means in axially spaced relationship to said flange means, spring means interposed between said abutment means and the upper end of said tubular member and continuously urging said flange means to exert radial and axial pressure on said first holding means, and second holding means supported by said tubular member in axially spaced relationship to said first holding means and operable to axially and frictionally engage and hold the yarn sleeve inserted into said tubular member.

4. In a yarn winding device, especially for spinning

and twisting machines, supporting means, a substantially vertical tubular member rotatably journaled in said supporting means and adapted to receive therein at least a portion of a yarn sleeve for supporting a cop, first annular yieldable holding means supported by the upper end portion of said tubular member and adapted to allow the passage of at least a portion of said yarn sleeve therethrough when inserting said yarn sleeve into said tubular member, said first annular yieldable holding means comprising annular segments with a conical peripheral surface and yieldable spring means respectively interposed between said segments for continuously urging the same away from each other, a bushing having a flanged portion with an inner conical surface corresponding to the peripheral surface of said segments and also comprising a skirt portion connected to said flanged portion and surrounding the upper end portion of said tubular member in radially spaced relationship thereto, radially inwardly extending abutment means connected to said skirt portion in axially spaced relationship to said flanged portion, spring means interposed between said flanged portion and said abutment means and continuously urging said flanged portion to move in axial direction toward the adjacent end of said tubular member to thereby move said segments radially inwardly and exert a clamping and holding pressure on a yarn sleeve inserted into said tubular member through said first holding means, and second holding means supported by said tubular member in spaced relationship to said first holding means for likewise frictionally engaging and holding the yarn sleeve inserted into said tubular member.

5. In a yarn winding device, especially for spinning and twisting machines, supporting means, a tubular member rotatably journaled in said supporting means and adapted to receive therein at least a portion of a yarn sleeve, said tubular member having a corrugated inner surface, and annular holding means arranged within the grooves formed by the corrugation of said tubular member and adapted to receive and frictionally connect to said tubular member a yarn sleeve at least partially inserted into said tubular member.

6. In a yarn winding device, especially for spinning and twisting machines, supporting means, a substantially vertical tubular member rotatably journaled in said supporting means and adapted to receive therein at least a portion of a yarn sleeve, first annular holding means arranged at the upper end of said tubular member and adapted to receive and frictionally connect to said tubular member a yarn sleeve at least partially inserted into said tubular member, permanent magnetic supporting means spaced from said first holding means in axial direction of said tubular member and provided with means for engaging the lower end of the yarn sleeve to be inserted in said tubular member to thereby axially locate said yarn sleeve, and second holding means supported by said tubular member and supporting said magnetic supporting means.

7. A yarn winding device according to claim 6, in which the magnetic supporting means forms a supporting sleeve for engaging a yarn sleeve to be introduced in said tubular member from below.

8. In a yarn winding device, especially for spinning and twisting machines, supporting means, a substantially vertical tubular member rotatably journaled in said supporting means and adapted to receive therein at least a portion of a yarn sleeve, said tubular member being open at both ends so as to allow the insertion of a yarn sleeve from the lower end of said tubular member, and annular holding means supported by said tubular member for frictionally engaging and holding a yarn sleeve introduced into said tubular member.

9. In a yarn winding device, especially for spinning and twisting machines, supporting means, a substantially vertical tubular member rotatably journaled in said supporting means and adapted to receive therein at least a

portion of a yarn sleeve for supporting a cop, a resilient slit bushing arranged at the lower end of said tubular member and yieldable in radial direction to allow the introduction of a yarn sleeve therethrough from the lower end of said tubular member into the latter, said bushing being provided with means axially engaging from below a yarn sleeve introduced through said bushing into said tubular member, first holding means supported by said tubular member adjacent said slit bushing for holding the same, and second holding means spaced from said first holding means in axial direction of said tubular member for frictionally connecting an inserted yarn sleeve to said tubular member.

10. A set of cop-receiving yarn sleeves adapted to partially telescopically engage each other for use in connection with an arrangement according to claim 9, whereby successive yarn sleeves introduced through the bushing will be adapted to move the respective preceding yarn sleeve through said tubular member and partially out of the same.

11. A set of yarn sleeves according to claim 10, in which successive yarn sleeves have an inner taper tapering by the wall thickness of the respective preceding sleeve.

12. A yarn sleeve for use in connection with a yarn winding device according to claim 9, in which each yarn sleeve has an inner and outer cone of such taper that each sleeve can be partially introduced from below into another sleeve.

13. In a yarn winding system, especially for spinning and twisting machines, supporting means, a substantially vertical tubular member rotatably journaled in said supporting means, a substantially vertical support extending from the inside of said tubular member in axial direction beyond the upper end thereof, first holding means associated with said vertical support for holding the same in a desired stationary position relative to said tubular member, a plurality of telescopically interengaged yarn sleeves displaceably surrounding said vertical support, and second holding means respectively associated with the lower ends of said yarn sleeves for holding the same in desired positions with regard to said vertical support.

14. In a yarn winding device, especially for spinning and twisting machines, supporting means, a tubular member open at both ends and having cylindrical outer surface means rotatably journaled in said supporting means for permitting rotation of said tubular member, a yarn sleeve having a maximum outer diameter less than the smallest inner diameter of said tubular member to thereby permit passing said yarn sleeve from the outside of said tubular member through said tubular member from one end to and through the other end thereof, holding means carried by said tubular member and rotatably connecting said yarn sleeve to said tubular member, and driving means engaging the outside of said tubular member for rotating the same and thereby said yarn sleeve.

15. In a yarn winding device, especially for spinning and twisting machines, supporting means, a tubular member open at both ends and having cylindrical outer sur-

face means rotatably journaled in said supporting means for permitting rotation of said tubular member, a yarn sleeve having a maximum outer diameter less than the smallest inner diameter of said tubular member to thereby permit passing said yarn sleeve from the outside of said tubular member through said tubular member from one end to and through the other end thereof, holding means carried by said tubular member and variable in position along at least a portion of the length of said tubular member to thereby selectively vary the location of support for said tubular member and thereby also to vary the position of the ends of said yarn sleeve relative to said tubular member, said holding means rotatably connecting said tubular member to said yarn sleeve, and driving means engaging the outside of said tubular member for rotating the same and thereby said yarn sleeve.

16. A yarn winding device according to claim 14, in which said holding means frictionally engages and holds said yarn sleeve so as to normally prevent axial displacement of said yarn sleeve, said holding means being adapted in response to a certain pulling pressure in axial direction of said tubular member to permit axial movement of said yarn sleeve relative to said tubular member for adjustment of said yarn sleeve and its removal from said tubular member.

17. A yarn winding device according to claim 14, in which said holding means are radially yieldable and elastic.

18. A yarn winding device according to claim 14, in which said holding means are formed by yieldable elastic rings.

19. A yarn winding device according to claim 14, in which said holding means are formed by elastic annular members variable as to radial pressure exertable thereby.

20. In a yarn winding device, especially for spinning and twisting machines, supporting means, a tubular member open at both ends and having cylindrical outer surface means rotatably journaled in said supporting means for permitting rotation of said tubular member, yarn sleeve means having a maximum outer diameter less than the smallest inner diameter of said tubular member to thereby permit passing said yarn sleeve means from the outside of said tubular member through the latter from one end to and through the other end thereof, first annular holding means arranged at one end of said tubular member for frictionally engaging and holding adjacent portions of said yarn sleeve means, at least a further annular holding means arranged within said tubular member and likewise frictionally engaging and holding said yarn sleeve means, and driving means engaging the outside of said tubular member for rotating the same and thereby said yarn sleeve means.
